INVENTOR
John M. Deemer

UNITED STATES PATENT OFFICE.

JOHN M. DEEMER, OF NEW YORK, N. Y.

TOY.

1,319,379.

Specification of Letters Patent.

Patented Oct. 21, 1919.

Application filed April 18, 1918. Serial No. 229,248.

To all whom it may concern:

Be it known that I, JOHN M. DEEMER, a citizen of the United States, and resident of New York, county of New York and State of New York, have invented certain new and useful Improvements in Toys, of which the following is a specification, reference being had to the accompanying drawing, forming a part thereof, in which 10 similar letters of reference indicate corresponding parts.

This invention relates to toys, and has for its object to supply a device of this character which comprises, in a simple and inexpensive construction, images of either human beings or lower animals and means adapted to oscillate and maintain them in lifelike motion without the aid of expensive spring-motor or other complicated mechanism.

The device comprises a manually operable rocker and a normally upright figure representation of an animate body or plurality thereof in pivotal connection with said rocker and having a depending weighted member, all as hereinafter fully described and specifically set forth in the annexed claims.

In the accompanying drawings, forming part of this specification, Figure 1 is a plan view of a blank adapted to be bent into shape producing my improved rocker. Fig. 2 is a longitudinal sectional view of the toy completely assembled. Fig. 3 is a vertical sectional view taken on the line 3—3 of Fig. 2. Fig. 4 is a longitudinal sectional view showing the device in motion. Fig. 5 is a longitudinal sectional view illustrating a modification. Fig. 6 is a similar view 40 showing a further modification; and Fig. 7 is a cross section taken on the line 7—7 of Fig. 5.

In the example of my invention illustrated in the drawings a rocker A, is formed from a single disk of sheet metal or other pliable substance, as compressed fiber, shown in blank by Fig. 1 of said drawings. This blank is provided with slits 1 and 2, making oppositely located parts 3, which are each 45 pierced with a hole 4, and adapted when bent downwardly, or inwardly on the dotted lines 5, to form the hangers B, to which the images hereinafter described are pivoted, and also the slots b, through which said 55 images swing.

To form the rocker A, the segments 6,

are bent on the dotted lines 5, into position shown by Fig. 3 of the drawings, thus producing a rocker embodying, in integral formation, sides C, a flat top or platform D 60 and the hangers B, having their holes 4 in lateral register with each other making bearings for engagement with pivots, or pins E, for supporting images, as F, G and H. Said images may be composed of sheet 65 material embodying armed figure representations of soldiers in contest, shown by Figs. 2, 3 and 4 of the drawings. They may also comprise figure representations of various kinds of animate bodies engaged in 70 a variety of actions, as the flat images G, representing dancers and each having swinging arms and legs, as illustrated by Fig. 5 of the drawings; or the full-jointed figure H, shown in Fig. 6. 75

Each image has a downwardly extended member I, having fixed thereto a weight J, of such proportion as to maintain the image in normally upright position at right angles to the plane of the rocker top when the device is at rest; and said images are respectively mounted, in swinging relation with the rocker, on a pivot, or pin E, washers e, being provided to prevent lateral movements of the images. 85

It is noteworthy that the slots b, are arranged on opposite sides of the longitudinal center of the top D, of the rocker, whereby the images may readily swing back and forth without liability of actual contact while 90 at the same time, when in motion, the appearance of contest, illustrated by the construction shown in Figs. 2 and 4, where the images bear arms, is maintained. However, I do not confine myself to the employment 95 of images in contest, as the invention may be employed to depict dancing human figures or figures of various animals in swinging motion, moving upwardly and downwardly.

In Fig. 5 of the drawings I have illustrated a pair of dancing figures each having a swinging arm 7 and a swinging leg 8. In this construction the hangers B, are respectively provided with a slot 9, whereby the figures may be caused to swing and also 100 move to and fro, by gravity, on a plane parallel with the top of the rocker when said rocker is operated and the slots 9, are at an angle to the plane of the horizontal base upon which the rocker is placed. 105

In Fig. 6 of the drawings the image H, has a rounded, or full-bodied trunk and

jointed arms 10 and legs 11, and the extension I, is composed of wire having a loop i, for engaging its supporting pivot E. In this construction the legs 11, are of such 5 length as to have the soles of their feet normally contact with the platform, or top of the rocker, whereby said soles of the feet will tap on said platform to produce a life-like dancing action when the rocker is in 10 motion, the figure oscillated and swinging motion is imparted to its arms and legs.

In the simplest form of my invention the rocker may be open at the bottom; or a protective bottom 12, may be secured between 15 the side walls C, as shown by Fig. 5 of the drawings.

In the operation and use of the invention it is simply necessary for a user to tap either end of the platform D, with the finger 20 tips. This imparts rocking motion to the rocker causing the images to move upwardly and downwardly and also swing or oscillate back and forth on their pivots by means of the weights J, which are caused to oscillate by the rocking motion imparted to the 25 rocker, the images continuing their movements upwardly and downwardly and to and fro, in a lifelike manner, as long as rocking motion is imparted to the rocker, 30 the arms and legs, when pivoted, or jointed arms and legs are employed, also continuing to swing during the continuance of said rocking motion.

I do not confine myself to the specific 35 details of mechanical construction and process of manufacture as herein shown and described, as under the spirit and scope of my invention I believe that I am entitled to employ variations of construction comprising 40 mechanical and structural equivalents for the several parts of the device.

While I have specifically described my invention as related to images of animate bodies figure representations of various moving 45 things may also be employed without departing from the spirit of my invention. For instance, instead of the images shown I may substitute miniature air ships or other devices adapted to have movement imparted 50 thereto.

Having thus described my invention, what I claim as new, and desire to secure by Letters Patent, is:—

1. A toy comprising a segmental rocker 55 and a swinging image of an animate body, said image having a pendulum-member extended therefrom, said image in pivotal relation with said rocker, whereby rocking motion imparted to said rocker oscillates 60 said image.

2. In a toy, the combination of a segmental rocker and an image of an animate body, said image having a downwardly extended member, and a weight on said member; said image in pivotal relation with said

rocker, whereby rocking motion imparted to said rocker oscillates said image.

3. In a toy, the combination of a rocker embodying two side segments and a flat platform having a slot therein; with an image of an animate body in pivotal relation with said rocker and extended through said slot, said image having a weighted member dependent therefrom, whereby rocking motion imparted to said rocker oscillates 75 said image.

4. In a toy, the combination of a rocker embodying two side segments and a flat platform having a slot therein; with an image of an animate body, said image in 80 pivotal relation with said rocker and extended through said slot, and a weighted member extended downwardly from said image, and means pivoting and hanging said image, said image adapted to be oscillated by means of said rocker when rocking motion is imparted thereto.

5. In a toy, the combination of a rocker embodying two side segments and a flat platform having a plurality of slots therethrough; with a plurality of images, said images in pivotal relation with said rocker and extended through said slots and each having a weighted extension, and means pivoting and hanging said images, said images adapted to be moved upwardly and downwardly and oscillated by means of said rocker when rocking motion is imparted thereto.

6. In a toy, the combination of a rocker 100 embodying two side segments and a flat platform having a slot therethrough; with an image having swinging arms and legs, and a weighted extension, said extension passing through said slot, said image in pivotal relation with said rocker, and means pivoting said image, said image adapted to be oscillated by means of said rocker when rocking motion is imparted thereto.

7. In a toy, the combination of a rocker 110 embodying two side segments and a flat platform having a slot therethrough; with an image having jointed and swinging arms and legs and a weighted extension, said extension passing through said slot, and hangers having slots parallel with the plane of said platform, and lateral pivots engaging said slots and supporting said images whereby, when rocking motion is imparted to said rocker, said image is caused to move 120 upwardly and downwardly and to and fro and swinging motion is imparted to its legs and arms.

8. A toy comprising a segmental rocker, a pendulum-member in pivotal relation 125 with said rocker, and a figure representation of a moving object, said object extended upwardly from said pendulum-member.

9. In a toy, the combination of a pendulum-member, a figure representation of a 130

moving object extended upwardly from said pendulum member; with a rocker having a segmental tread adapted to bear on a horizontal plane, said pendulum member in pivotal relation with said rocker whereby, when rocking motion is imparted to said rocker said pendulum-member and its connected parts are caused to oscillate.

10. In a toy, the combination of a rocker embodying two side segments and a flat platform having a slot therethrough; with an image having swinging and jointed arms and legs, and a weighted extension, said extension passing through said slot, and 15 hangers having slots, and lateral pivots en-

gaging said slots and supporting said images whereby, when rocking motion is imparted to said rocker, said image is caused to move upwardly and downwardly and to and fro and swinging motion is imparted 20 to its legs and arms.

In testimony that I claim the foregoing as my invention, I have signed my name in presence of two witnesses, this seventeenth day of April, 1918.

JOHN M. DEEMER.
